UNITED STATES PATENT OFFICE.

MILTON KELLOGG, OF NEW YORK, N. Y.

FOLDABLE COVER FOR DICTATING-MACHINES AND THE LIKE.

1,144,417.

Specification of Letters Patent. Patented June 29, 1915.

Application filed June 11, 1913. Serial No. 773,036.

To all whom it may concern:

Be it known that I, MILTON KELLOGG, a citizen of the United States, residing in the borough of Manhattan, city, county, and 5 State of New York, have invented certain new and useful Improvements in Foldable Covers for Dictating-Machines and the like, of which the following is a specification.

This invention relates to foldable covers 10 for dictating machines, phonographs, stock tickers, typewriters and the like, and aims to provide improvements therein.

Covers of the kind at present in use cannot be folded sufficiently flat, and with sufficient 15 ease, to enable them to be conveniently folded and stowed away, when removed from the apparatus over which they are placed.

The present invention overcomes the foregoing 20 objections and provides a cover which can be folded so as to lie perfectly flat, without wrinkling, and which when removed from the apparatus over which it is placed will easily and inherently tend to fall 25 into its flat folded position. When folded the cover lies perfectly flat and smooth and can be laid flat upon a table or in a drawer without occasioning any inconvenient obstruction.

The invention will be described more 30 fully in connection with the accompanying drawings, wherein—

Figure 1 illustrates a development of the body and end pieces constituting the cover; 35 Fig. 2 is a front elevation of the cover, extended and as it appears when in place over a piece of mechanism; Fig. 3 is an end elevation of the cover in extended or open position; and Fig. 4 is a view of the cover in 40 folded position, parts being broken away to show more clearly the underlying parts.

In said drawings, A A indicate the end pieces and B the body piece, which parts are most usually and preferably made of fabric 45 having a rubber, or rubber-like, coating. The end pieces A may have practically any desired outline. As shown the end pieces A have somewhat the shape of a semi-ellipse on its minor axis. These end pieces 50 may, however, have a variety of outlines, and may include a variety of curves, as well as straight lines.

In laying out the end pieces A, a triangle is constructed within the same, having its 55 apex at the center line of fold b of the cover. As ordinarily constructed, covers of the

kind referred to have their body portions constructed as a simple rectangular figure, in length corresponding to the perimeter of the sides of the end pieces. When such a 60 body piece is united to an end piece having any other outline than that of a triangle, the covers will not fold without wrinkling nor lie flatly, as can be readily verified by constructing a cover, or by folding one of the 65 ordinary covers upon the market.

In constructing the body piece B of applicant's invention straight lines b^2 b^2 are drawn at the sides, corresponding in length to the sides a^2 a^2 of the triangle constructed 70 within the end piece B. On the outside of these lines b^2 b^2 are laid out geometrical figures b^3 b^3 b^3 corresponding in shape to the figures a^3 a^3 of the end pieces A, on the outside 75 of the sides a^2 a^2 of the triangles within the end pieces.

The body piece B and the end piece A are united along the perimeters of the figures a^3 and b^3 . Covers constructed of a body piece and an end piece or pieces thus shaped 80 and united will fold perfectly without wrinkling and will lie perfectly flat when folded. The lines b^2 b^2 at opposite sides of the body piece B may be parallel or may converge or diverge. As shown on the drawing the lines converge. In such construction the corners c, Fig. 2, of the cover when extended are not formed at the line of union 85 of the parts A and B of the cover, but are preferably formed at bends in the part A 90 of the cover. By this construction the tendency of the cover, when extended, is to collapse inwardly, thus providing an inherent folding or tendency to fold, when the cover is removed from the part over which it is 95 placed. Furthermore, by such construction the bottom edges of the cover close or tend to close, inwardly around the object over which the cover is placed, the cover thus fitting snugly at its bottom edges around the object over which it is placed.

In symmetrical covers, such as illustrated in the drawings, the end pieces A fold in their middle, along the line a bisecting the apex of the triangle constructed within the 100 end piece A. In most cases the line of fold in the end piece will bisect the apex of the triangle constructed therein. In some irregular shapes of covers the line of fold in the end piece may be best determined by experiment. The folding of the cover may be 105 facilitated by creasing the end piece along

the line of fold, as at *a*. Preferably, however, a line of stitches *a*⁵, Figs. 3 and 4, is run along the line of fold, producing at the end pieces a pronounced inherent tendency, 5 or effect, of folding inwardly along the line of fold when the cover is removed from the object which it covers.

From the foregoing it is apparent that the invention may receive mechanical expression 10 in a variety of embodiments other than that illustrated and described.

What I claim is:—

1. A foldable cover comprising a body-piece and an end-piece, said end-piece having 15 edge portions on the outside of the largest triangle which may be inscribed within said end-piece, said body-piece having edge portions contiguous to said edge portions of said end-piece, of a corresponding outline 20 and said body-piece and end-piece being connected at said edge portions, said body-piece and said end-piece each being adapted when so connected to be folded into two parts, and when so folded, to lie flat.

25 2. A foldable cover comprising a body-piece and two end-pieces, said two end-pieces being located at opposite sides of said body-piece, said end-pieces having edge portions on the outside of the largest triangle which 30 may be inscribed within said end-pieces, said body-piece having edge portions contiguous to said edge portions of said end-pieces, and of a corresponding outline and said end-pieces being connected to said body-piece at 35 said edge portions, said body-piece and said end-pieces each being adapted to be folded when so connected into two parts, and when so folded, to lie flat.

3. In a foldable cover, the combination of

a body-piece and an end-piece, said end-piece being of substantially three-sided configuration and having edge portions outside of two sides of a triangle which may be inscribed within said end-piece, each side of 40 said body-piece being of four-sided configuration and having at the side adjacent said end-piece a portion outside of a line connecting its upper and lower corners corresponding to the adjacent outside portion 45 of said end-piece, and secured thereto at 50 its edge.

4. In a foldable cover, the combination of a body-piece and two end-pieces, each of said end-pieces being of substantially three-sided configuration and having edge portions outside of two sides of a triangle which may be inscribed within said end-piece, said body-piece being folded on a line substantially intersecting the peaks of the end-pieces and each side of said body-piece being, when 55 folded, of substantially four-sided configuration and having at the side adjacent each of said end-pieces a portion outside of a line connecting its upper and lower corners corresponding to the adjacent outside portion 60 of said end-pieces and secured thereto at its edge, and each of said end pieces being creased along a line meeting said body fold so as to tend to fold between the sides of said 65 body-piece.

In witness whereof, I have hereunto signed my name in the presence of two subscribing witnesses.

MILTON KELLOGG.
